SLIDER FOR SLIDE FASTENERS

Alfred E. Carlile, Meadville, Pa., assignor to Talon,
Inc., a corporation of Pennsylvania

Application June 7, 1941, Serial No. 397,035

2 Claims. (Cl. 24—205)

This invention relates to slide fasteners and, in particular, to the provision of a new and improved slider for slide fasteners and a new and improved method of slider assembly.

It is the object of this invention to provide an automatic lock slider for slide fasteners, which is cheap, and which may be economically and conveniently assembled.

It is a further object of this invention to provide such a slider wherein the lock operating pull tab is of such construction and is assembled in such manner that accidental removal thereof after assembly is totally prevented.

These and other objects and advantages of the invention will appear from the following description taken in conjunction with the accompanying drawing which forms a part thereof, and will be pointed out in the appended claims.

In the drawing:

Fig. 1 is a fragmentary view, in perspective, of a slide fastener embodying a slider constructed according to the principles of this invention;

Fig. 2 is a section taken substantially on the line 2—2 of Fig. 1;

Fig. 3 is a section taken substantially on the line 3—3 of Fig. 2;

Fig. 4 is a section taken substantially on the line 4—4 of Fig. 2;

Fig. 5 is a section taken substantially on the line 5—5 of Fig. 2;

Fig. 6 is a fragmentary view, in perspective, illustrating the manner in which the lock biasing means is assembled; and

Fig. 7 is a perspective view of a conventional pull tab having oppositely directed pivot truncations with separated ends.

In United States Letters Patent No. 1,966,457, granted July 17, 1934, to Samuel H. Norton and Pedar Nedal, a lock slider for slide fasteners is shown, wherein the locking member is in the form of a hollow sheet metal member with top, side walls and end walls. This locking member overlies a longitudinal lug on the front wing of the slider body and is pivotally secured thereto at one end. The free end of the locking member is provided with locking projections adapted to project into the channel of the slider into locking engagement with the interlocking fastener members of the fastener.

In order normally to project these locking projections into locking engagement, the locking member is constantly biased toward locking position by a leaf spring secured to the longitudinal lug on the slider wing and engaging the interior of the locking member for constantly biasing the

locking member, about its pivot, toward locking position. Because of their small size, it is extremely difficult to handle and assemble such leaf springs which must be attached to the lug on the slider before attachment of the locking member. According to this invention, these difficulties of assembly are eliminated by the use of a biasing member of resilient material such as rubber, synthetic rubber or the like, the attachment of the locking member to the slider being accomplished prior to insertion of the resilient biasing member.

Furthermore, the pull tab is provided at its inner end with a continuous integral pivot bar and the central portion of the above-described lug on the slider body is removed to form a pair of spaced lugs between which the pivot bar is accommodated. The pull tab locking member and slider body are maintained in operative relation by the attachment of the locking member to the slider body, accidental detachment of the pull tab by twisting being totally prevented by the continuity of its pivot bar.

Fig. 1 of the drawings shows a slider according to this invention applied to a conventional slide fastener comprising a pair of complementary stringers 10 and 11 secured together at their lower ends. Each stringer comprises a tape 12 with a thickened reinforced edge 14, to 20 which is secured a row of predeterminedly spaced interlocking fastener members 15. The lower ends of the reinforced edges 14 are secured together by a conventional bottom stop or bottom end fitting 16 clamped therebetween. Longitudinal movement of the slider on the interlocking fastener members 15 of the stringers 10 and 11 causes progressive engagement and disengagement of the interlocking fastener members 15 to open and close the fastener.

The slider is generally designated 20 and comprises a pair of plate-like wings 21 and 22 provided with side flanges 23 and secured together in predetermined spaced relationship by a wedge or neck member 24 providing integral connection of their upper ends. The inner surfaces of the flanges 23 cooperate with the surfaces of the wedge or neck member 24 to form an upwardly diverging guide channel for the rows of interlocking fastener members 15 which are confined therein. While the rear wing member 22 has a flat outer surface, a pair of upstanding lugs extends outwardly from the outer, front surface of the front wing member 21. These lugs are substantially spaced longitudinally of the slider body and the upper lug 25 may be designated the pivot

lug, because the locking member is pivoted thereto, pivot recesses 26 (Fig. 4) being provided at opposite sides of the pivot lug 25 for this purpose. The other lug 27 may be designated the locking member limiting lug since it is provided at opposite sides with recesses 28 which accommodate projections or limiting stops formed at the lower end of the locking member for predeterminedly limiting movement of the locking member about the pivot recesses 26, as will hereinafter most clearly appear.

Locking projection accommodating apertures 29 (Fig. 5) extend through the front wing 21 at each side of the locking member limiting lug 27 and provide for access of the locking projections 38 of the locking member into the channel of the slider body.

The locking member is generally designated 30 and comprises a hollow sheet metal member having a generally rectangular top wall 31, similar side walls 32, a lower end wall 33 and an upper end wall 34. The central portion of each side wall 32 is cut away, as shown at 35 (Fig. 2), to accommodate the pivot bar or pivot portion 49 at the inner end of the pull tab 45.

Each side wall 32 is provided at its upper end with a struck-in portion which forms a pivot projection or trunnion 36 closely engaging one of the pivot recesses 26 (Fig. 4) pivotally to secure the upper end of the locking member 30 to the pivot lug 25. The lower end of each side wall 32 is provided with a similar depression which forms a pair of limiting stops 37 which cooperate with the above-described recesses 28 predeterminedly to limit movement of the lower end of the locking member 30, both inwardly of the slider body and outwardly of the slider body, as shown in Fig. 5. Adjacent its lower or free end, each side wall 32 is provided with a locking projection or locking prong 38, adapted to project through one of the apertures 29. These locking prongs 38 are spaced longitudinally with respect to one another a distance equal to the pitch of the fastener whereby both may engage simultaneously in a space between adjacent interlocking fastener members 15.

In order that the locking member shall be constantly biased toward locking position, a block 40 of resilient material such as rubber, synthetic rubber, or the like, is secured between the upper end wall 34 of the locking member 30 and the upper side of the pivot lug 25 which is provided with a notch 25a (Fig. 2) at that side to maintain the block 40 in position. This block 40 is assembled under compression, whereby its expansive force constantly urges the locking member 30 clockwise, as seen in Figs. 1, 2 and 3. The adjustment of the force exerted by the block may be accomplished by variation in the position of the upper end wall 34 of the locking member with respect to the upper end edges 32a (Fig. 6) of the side walls 32.

Shown in dash lines in Fig. 2 is the position of the end wall 34 wherein no compression will be applied to the block 40 in the locked position of the slider, as shown in that figure. When, however, the end wall 34 is bent down from the dash line position to the full line position shown in Fig. 2, predetermined initial compression is applied to the block 40. This compression is, of course, increased when the locking member 30 is moved in counterclockwise direction from the locking position shown in Fig. 2 to its unlocked position (Fig. 5). In this unlocked position, the locking prongs or locking projections 38 of the

locking member are withdrawn through the apertures 29 from the channel of the slider, as shown in Fig. 5.

The manner in which the locking member 30 and biasing member, or block 40, are assembled to the body of the slider is as follows. The locking member 30 is stamped from a flat sheet and the depressions forming trunnions 36 and stops 37 are placed therein in suitable manner. The side walls 32 and lower end wall 33 are bent down to their final position, while the upper end wall 34 is bent to the intermediate position shown in Fig. 6. The locking member is then snapped over the lugs 25 and 27 (subsequent to placement of the pivot portion or pivot bar 49 of the pull tab in the cut-away portion 35 of the side walls), whereby the pivot recesses 26 are closely engaged by the struck-in projections or trunnions 36 and stops 37 are loosely confined in the recesses 28, as shown in Fig. 5. Thereafter, a strip 39 of rubber, synthetic rubber, or the like, is placed between the upper surfaces of the upper end wall 34 of the locking member 30 and the upper side edges 32a of the side walls 32 thereof, and the upper end wall 34 is bent inwardly in suitable manner from the intermediate position shown in Fig. 6 to the position shown in Fig. 2, whereby the sharp upper end edges 32a of the side walls 32 and the side edges 34a of the upper end wall 34 will shear off a section of the strip 39 equal in length to the distance between the side walls 32. This section forms the above-described block 40 which is the biasing member of the slider.

The conventional type of pull tab is shown in Fig. 7. The pull tab, generally designated 41, is of plate-like form, provided with a thong-receiving aperture 42 at its outer end and having a portion of its inner end slotted or cut away to form a pair of legs 43 terminating in oppositely disposed inwardly directed trunnions or pivot projections 44, the pivot projections being reduced toward their ends. These trunnions or pivot projections 44 are adapted to extend into the cut-away portion 35 of the side walls, whereby they are disposed between the front face of the front wing 21 and the locking member 30. Tension applied to the pull tab 41 thus moves the locking member 30 in counterclockwise direction, as shown in Figs. 1, 2 and 3, from the position of Fig. 2 to the unlocked position (Fig. 5) against the biasing member or resilient block 40.

While such pull tabs are generally effective, nevertheless, in operation, the application of manual twisting forces often causes undue separation of the pivot projections or trunnions 44, whereby they can escape from the space between the locking member 30 and the front surface of the wing 21, causing accidental detachment of the pull tab from the slider.

In order totally to obviate the above-described undesirable accidental separation of the pull tab and slider, I have provided a new and improved pull tab construction, especially adapted for use with the above-described slider construction, and forming a part of the preferred embodiment thereof. This pull tab construction is shown in Figs. 1 to 4 and comprises a plate-like member 45 provided with a thong-receiving aperture 46 at its outer end and having an aperture 47 at its inner end, which forms a pair of legs 48 similar to the above described legs 43, but connected at their lower ends by a single integral pivot bar 49 extending continuously from leg to leg. Since the main portion of the pull tab forms with the legs 48 and pivot bar 49 what is, in effect, a closed loop, acci-

dental displacement of the pull tab 45 from the slider cannot occur so long as the locking member 30 is attached to the slider body.

From the above description, it will clearly appear that I have provided a new and improved lock slider construction which may be cheaply and conveniently manufactured and wherein accidental detachment of the pull tab from the slider is prevented by the construction of the pull tab. It will likewise appear that I have provided a new and improved method for assembling such a slider, wherein the biasing means is applied after the locking member is attached to the slider body and wherein the biasing force may be varied at will by adjustment of a part of the locking member.

It is, of course, to be understood that the above description is merely illustrative and in nowise limiting and that I desire to comprehend within my invention such modifications as are included within the scope of the appended claims.

Having thus fully described my invention, what I claim as new and desire to secure by Letters Patent is:

1. In a slider for slide fasteners, a pair of connected wings forming a fastener member guide channel therebetween, one of said wings having a locking prong receiving aperture communicating with said guide channel, a lug projecting outwardly from said last-named wing, a locking member pivotally connected adjacent one end to said lug and having a locking prong extensible through said aperture into and out of said channel upon pivotal movement of said locking member, said locking member having a wall extend-

ing over said lug, and a biasing member comprising a block of resilient material between said lug and said wall of said locking member and acting on said wall for normally urging said locking member toward locking position wherein said locking prong is projected into said guide channel, said wall being bendable with respect to said locking member for adjusting the compressive force exerted by said biasing member.

2. In a slider for slide fasteners, a pair of connected wings forming a fastener member guide channel therebetween, one of said wings having a locking prong receiving aperture communicating with said guide channel, a lug projecting outwardly from said last-named wing and having a biasing member retaining notch in its upper side, a locking member pivotally connected adjacent its upper end to said lug and having a locking prong extensible through said aperture into and out of said channel upon pivotal movement of said locking member to lock and unlock said slider, said locking member having a wall at its upper end extending over the notch in said lug, a biasing member comprising a block of resilient material in said notch between said lug and said wall of said locking member and normally urging said locking member toward locking position wherein said locking prong is projected into said guide channel, and a pull member operatively connected to said locking member for manually moving said locking member to unlocked position against the force exerted by said biasing member.

ALFRED E. CARLILE.
